UNITED STATES PATENT OFFICE.

WILLIAM M. KENDRICK, OF DUXBURY, MASSACHUSETTS.

CRANBERRY-PICKER.

SPECIFICATION forming part of Letters Patent No. 600,204, dated March 8, 1898.

Application filed December 14, 1896. Serial No. 615,688. (No model.)

To all whom it may concern:

Be it known that I, WILLIAM M. KENDRICK, of West Duxbury, in the county of Plymouth and State of Massachusetts, have invented a new and useful Improvement in Cranberry-Pickers, of which the following, taken in connection with the accompanying drawings, is a specification.

My invention relates to a hand cranberry-picker; and it consists in a device by which the stripper can be adjusted in relation to the gathering-fork so as to make the picker adapted to gather small or large berries, the object being to so construct the instrument that the adjustment may be made by the user without the use of tools and without waste of time. This object I attain by the mechanism shown in the accompanying drawings, in which—

Figure 1 is a perspective view of a cranberry-picker with my adjusting device attached. Fig. 2 is a side elevation of the same, a part being represented as broken out to show more clearly the adjusting device. Fig. 3 shows in plan a sheet-metal plate which when bent forms a casing for the adjusting device.

In the drawings, A B B' A' represent the ground-framework of the machine. The handle consists of the longitudinal bar D, which is attached to the parts B and B' of the frame, as shown in Fig. 1.

E is a bar hinged at C to the bar D and has a forked end which engages with a staple F, connected to the stripper H. A spring L serves to throw up the bar E, which action causes the stripper H to be raised up. The stripper H has pivots, about which it swings. One of the pivots is shown at M. The forks are clearly noted by R R.

The above-mentioned parts are not new and need not be particularly described.

I will now describe the parts I consider new. The new parts constitute together a device by which the distance between the ends of the forks R R and the plate H' (also shown at h in dotted lines) is regulated. This regulation or adjustment is quite important, as by it the picker may be made to work well for picking large or small berries.

The pivots M, upon which the stripper H is hung, are rigidly attached to the stripper, but

move freely in the swinging levers P. These swinging levers P are each attached to a pin, (shown at N, Fig. 2,) so that by moving the upper end of the lever back or forth the pivots M, about which the stripper turns, are adjusted so that when the stripper is down its plate H' (h) will occupy the desired place in relation to the ends of the forks R R. To hold the lever P in place, I have a spring-wire S S'. This wire is bent, so as to pass through the upper end of the lever P. The wire S S' is bent down at right angles, as shown at Y, and engages with one of the holes T T, by which it is held securely in place, so that the lever P cannot move. To adjust the lever P, the user has simply to bend the wire S upward, so as to draw the part Y out of its hole and to move the lever to such a position as may be desired. This movement will cause the plate H' (h) of the stripper to assume the desired position in relation to the forks R R.

The thin plate (shown flat in Fig. 3) is provided with openings, as shown. The openings W W are for receiving the pivot M. The center opening allows the upper end of the lever to pass up through. When the thin plate V (shown in Fig. 3) is bent and attached, it appears as shown in Fig. 1.

I claim—

1. In a cranberry-picker, a stripper, swinging levers, to which it is pivotally attached, whereby its position in relation to the ends of the forks is regulated, and mechanism for adjustably holding said swinging levers in place, substantially as and for the purpose set forth.

2. In a cranberry-picker, the combination of a stripper having pivots about which it turns; with a swinging lever adapted to hold said pivots, a plate V having holes T T and a spring-wire catch S S' substantially as and for the purpose set forth.

In testimony whereof I have signed my name to this specification, in the presence of two subscribing witnesses, on this 23d day of November, A. D. 1896.

WILLIAM M. KENDRICK.
